(57) **CLAIM**

The ornamental design for a baler light, as shown and described.

DESCRIPTION

FIG. 1 is a top, front, right side perspective view of a baler light, showing a first embodiment of my new design;

FIG. 2 is a right side elevation view thereof;

FIG. 3 is a left side elevation view thereof;

FIG. 4 is a front elevation view thereof; and

FIG. 5 is a rear elevation view thereof.

FIG. 6 is a top plan view thereof;

FIG. 7 is a bottom plan view thereof;

FIG. 8 is an enlarged perspective view thereof taken along arc **8-8** in FIG. 1;

FIG. 9 is a top, front, right side perspective view of a baler light, showing a second embodiment of my new design;

FIG. 10 is a right side elevation view thereof;

FIG. 11 is a left side elevation view thereof;

FIG. 12 is a front elevation view thereof; and

FIG. 13 is a rear elevation view thereof.

FIG. 14 is a top plan view thereof;

FIG. 15 is a bottom plan view thereof;

FIG. 16 is an enlarged perspective view thereof taken along arc **16-16** in FIG. 9;

FIG. 17 is a top, front, right side perspective view of a baler light, showing a third embodiment of my new design;

FIG. 18 is a right side elevation view thereof;

FIG. 19 is a left side elevation view thereof;

FIG. 20 is a front elevation view thereof; and

FIG. 21 is a rear elevation view thereof.

FIG. 22 is a top plan view thereof;

FIG. 23 is a bottom plan view thereof; and

FIG. 24 is an enlarged perspective view thereof taken along arc **24-24** in FIG. 17.

FIGS. 1-24 show three embodiments of a baler light on the right side of a baler. Three additional embodiments are mirror images of the first three embodiments, with a baler light on the left side of the baler.

(Continued)

The broken lines depict environmental subject matter that forms no part of the claimed design.
